UNITED STATES PATENT OFFICE.

LORENZ FLICK, OF SAYLESVILLE, RHODE ISLAND, ASSIGNOR, BY MESNE ASSIGNMENTS, TO SAYLES FINISHING PLANTS, INC., OF SAYLESVILLE, RHODE ISLAND, A CORPORATION OF RHODE ISLAND.

ROLL-SUPPORT.

1,379,588.

Specification of Letters Patent. Patented May 24, 1921.

Application filed October 27, 1919. Serial No. 333,818.

To all whom it may concern:

Be it known that I, LORENZ FLICK, a citizen of the United States, residing at Saylesville, in the county of Providence, State of Rhode Island, have invented a certain new and useful Improvement in Roll-Supports, of which the following is a specification, reference being had therein to the accompanying drawings.

10 The features of the invention are applicable in a variety of connections in which rolls require to be mounted removably in working position. An important line of employment of the said features is in connection with rolls and the like on which a continuous web of sheet material is wound. When employed in such connection they facilitate the mounting of an empty roll or the like in position to be driven and to receive a load of the continuous sheet material, and they provide for ready and convenient removal of the wound roll. They are especially applicable in connection with the receiving rolls of textile machinery, but 25 are not confined to use in this connection, since they may be used for supporting and facilitating the removal of the rolls of paper-making machines, printing presses, etc.

Some of the features of the invention are 30 generically new, so far as I am aware, and the principles thereof admit of being embodied in various specific types of construction, with more or less variation in the form, etc., of the mechanism. A more specific 35 phase of the invention provides a special organization of novel and improved character. The drawings show the said organization with the various features of the invention embodied therein.

40 In the drawings, Figure 1 is a view partly in side elevation and partly diagrammatic showing the said organization in conjunction with certain of the elements of a mangle or cloth-calendering machine, the roll-support being in its closed or roll-supporting position.

Fig. 2 is a similar view showing the parts in the positions assumed by them upon the discharge of a roll.

50 Fig. 3 is a side elevation, Fig. 4 a back elevation, and Fig. 5 an end view, of the end portion or bracket of a carrier arm.

Fig. 6 is a side elevation, and Fig. 7 is a

plan of the bearing-member which is mounted upon the said end-portion or bracket. 55

Fig. 8 is a side elevation, and Fig. 9 a plan, of the operating lever which is combined with the said bearing-member.

Fig. 10 is a side elevation, and Fig. 11 an edge view, of one of the links connecting the said lever with the said bearing-member.

The drawings show the features of the invention embodied in an organized roll-support which is employed in connection 65 with the roll, 1, on which a web of cloth, 2, is wound as the said web leaves the top roll, 3, of the stack of rolls, 3, 4, 5, of a mangle or cloth-calendering machine. The said roll-support is movable toward and from 70 the roll 3, and the receiving and winding roll 1 applied to the roll-support is driven through frictional engagement between the periphery of the roll 3 and the exterior of the cloth already upon the roll 1. The said 75 engagement is provided for by arranging the roll-support so that the driven roll gravitates toward the driving roll 3, thereby insuring peripheral contact between the two rolls. The movability of the roll-support 80 enables it to recede from roll 3 as the diameter of the cloth wound thereon increases.

As the roll which is to be supported requires to be sustained at both ends thereof, and as the supports for both ends are essentially similar, it will be understood that 85 the following description of the organization at one end of the said roll applies equally in the case of both ends.

The illustrated roll-support comprises, essentially, a carrier 6 which gravitates toward roll 3, a bearing-member 10 movably connected with said carrier and adapted to receive a journal of roll 1, or of the spit or arbor which is employed in connection 90 with said roll, and means for controlling the said bearing-member whereby it may be operated to dispose it conveniently for the application of the said journal in mounting the roll in connection with the roll-support, 100 and then dispose it in proper relation to retain the journal during the performance of the operation or process in which the roll participates (herein the winding of the cloth upon the roll 1), and later on dispose 105 it so as to provide for the release of the roll.

The gravitating carrier is in this instance an arm 6, arranged to swing around an overhead pivotal axis toward and from the periphery of the driving-roll 3, the two arms 5 at the opposite ends of the roll 3 being pendent from a rockshaft 7 mounted in elevated bearings (not shown). The tendency of the roll-support and the roll 1 to gravitate toward the driving-roll 3 is increased 10 by means of a pressure-weight 8, mounted upon an outstanding branch 6^a of the arm 6, and adjustable upon the said branch to vary its effect in holding the roll 1, or the exterior of the cloth which has already been 15 wound thereon, against the periphery of the roll 3. At 9 is a clamping screw, by means of which the weight 8 is held in adjusted position upon the branch 6^a.

The bearing member 10 is in this instance 20 movably combined and connected with the carrier for the purposes of the invention by being hung pivotally at 10^a (Figs. 2, 3, 4 and 6) to the bracket 6^b, shown separately in Figs. 3, 4 and 5, constituting the lower 25 end of the arm 6. The said bearing-member 10 is formed with an open bearing 10^b, said open bearing being shown as occupied by a half-box or bushing 10^c to receive the journal 1^a of the roll 1. The pivotal hanging 30 of the bearing-member 10 upon the carrier permits it to assume either a depressed and rearwardly retracted receiving and discharging position like that shown in Fig. 2, which releases a journal occupying the bearing 35 and permits transverse discharge thereof or the introduction of a roll-journal, or the forwardly-advanced and upturned retaining position shown in Fig. 1, in which the said open bearing faces upwardly and 40 is adapted to hold the roll-journal, and so that the latter may revolve therein.

The means for controlling the said bearing-member 10 comprises in this instance an operating lever 11, pivoted to bracket 6^b at 45 11^a and having link-connection with the bearing-member. The operating lever 11 is shown separately in Figs. 8 and 9.

The two side-portions of the lever-hub are separated sufficiently to receive the 50 bracket-portion of the carrier-arm 6 between them, the lever being pivoted to the said bracket by means of the pivot-pin 11^a occupying a transverse hole 6^c in the bracket, the ends of said pin fitting holes 11^b, 11^b, 55 in the side-portions of the lever-hub. The cross-bar 11^c connects together the two side-portions. In one position of the operating lever the said cross-bar makes contact with the back of the bracket 6^b, and thereby limits 60 the play of the lever in the direction of movement by which the bearing-member is given its roll-supporting position. The links 12 (one thereof being shown separately in Figs. 10 and 11) are employed between 65 the lever and bearing-member, one at

each side of the latter two, the upper ends of the said links being engaged with opposite crank-pins 13, 13, Figs. 8 and 9, projecting transversely from the sides of the lever-hub, and their lower ends being engaged with crank-pins 14, 14, constituted by the opposite ends of a pin extending through a transverse hole 15, Fig. 6, in the bearing-member, located eccentrically with relation to the pivot 10^a of the said bearing-member. 70

When the operating lever 11 is swung about the axis of its pivotal connection with the carrier arm, forward and downward from the position occupied by the lever in 80 Fig. 2, the crank and link connection between the said lever and the bearing-member causes the bearing-member to be swung forward and upward about the axis of its pivotal connection with said carrier arm, from the retracted open position shown in Fig. 2 to the upturned position occupied in Fig. 1. The construction is such that in the extreme position of the lever which is shown in Fig. 1, namely with the cross-bar 11^c 90 resting against the back of the bracket portion of the carrier-arm, and with the bearing-member in its closed or roll-supporting position, the crank-pins 13, 13, are located slightly beyond centers; that is to say, are 95 located slightly beyond a straight line intersecting the axis of the lever-pivot 11^a and that of the crank-pins 14, 14. Consequently, the links and the cranks of the lever form a toggle-lock which locks the bearing-member 100 against movement due to the load supported by the bearing-member and tending to cause it to swing around its pivot. The lever 11 retains this position through the action of gravity upon its main outwardly extending 105 arm, to which a small weight 11^e is shown applied to increase the effect. When the operating lever is swung reversely, it acts through its connections with the bearing-member to swing the latter toward its releasing position shown in Fig. 2. The weight of a roll supported by the bearing-member will assist in this action. 110

At 16 is shown a table which is placed below the roll 1 in position to receive the 115 latter as its journal discharges or is removed from the bearing-member.

The release of the roll-journal from the roll-support frees the latter which thereupon gravitates rearward from the journal toward the roll 3, as in Fig. 2. As the roll-support assumes the position shown in Fig. 2, in which the pivot of lever 11 is carried forward relative to the weighted arm of such lever, the latter gravitates downward 120 toward and into its position occupied in Fig. 1, thereby automatically turning the bearing-member into position to support a roll-journal. 125

The extent of the opening movement of 130

the bearing-member may be limited, if desired, by constructing the parts so that in the said opening movement the back of the cross-bar 11^c of the operating lever shall 5 make contact with the back of the bracket 6^b, as in Fig. 2.

For the convenience of the operator in moving the operating lever 11 to give the bearing-member its open or discharging position, a cord or chain, 17, is shown, connected at one end with the said lever, and extending therefrom around guide sheaves, 17^a, 17^b, with its opposite end hanging down at the front of the receiving roll, and furnished with a handle, 17^a, to be grasped by the operator.

For the purpose of locking the roll-journal in the bearing of the bearing-member so as to prevent the roll-journal from jumping out of the said bearing, I provide one or each of the links 12 with a spur 12^a, which projects forwardly therefrom. In the closed position of the bearing-member that is illustrated in Fig. 1, 20 this spur extends over the open bearing, above the roll-journal, so as to prevent the latter from jumping. When the bearing-member is moved into its open or discharging position, the open top of the bearing is 25 moved downward away from this spur, and thereby the bearing is uncovered so as to release the journal of the roll.

While I have illustrated and described one form in which the invention may be 35 embodied, I am aware that many modifications may be made therein by any person skilled in the art, without departing from the scope of the invention as expressed in the claims. Therefore, I do not wish to be 40 limited to the particular form shown, or to the details of construction thereof, except in the case of the more specific claims below, but

What I do claim is:—

45 1. The combination, in a roll-support, with a gravitating swinging arm, of a journal-engaging member connected movably with said arm, a gravitating operating lever, a link-connection between said lever and the said journal-engaging member and through which said lever moves said member into working position for engagement with a roll-journal and withdraws such member to free the roll-journal, and stops 50 defining a position of said operating lever and link-connection in which they form a toggle-lock for the journal-engaging member.

60 2. The combination, in a roll-support, with a gravitating swinging arm, of a journal-engaging member connected movably with said arm, a gravitating operating lever pivoted to said arm, a link-connection between said lever and the said journal-engaging member and through which said

lever moves said member into working position for engagement with a roll-journal and withdraws such member to free the roll-journal, and stops defining a position of said operating lever and link-connection 70 in which they form a toggle-lock for the journal-engaging member.

3. The combination, in a roll-support, with a gravitating carrier, of a journal-bearing member connected movably with 75 said carrier, a gravitating operating lever pivoted to said carrier, a link-connection between said lever and said journal-bearing member and through which said lever moves said member into position to support 80 a roll-journal and withdraws such member to release the roll-journal, and stops defining a working position of the lever and link-connection in which they form a toggle-lock for the journal-bearing member. 85

4. Roll-supporting and releasing means comprising a support, a bearing-member hung to the said support, and movable with relation thereto from a position in which it engages a roll-journal and thereby supports the roll, to a position in which it releases said journal and frees the roll, and an operating lever combined with said bearing-member by connections which are self-locking to hold the bearing-member in the 95 position thereof which retains the roll-journal.

5. Roll-supporting and releasing means comprising a swinging arm, a bearing-member hung to the said arm and movable with 100 relation thereto from a position in which it engages a roll-journal and thereby supports the roll, to a position in which it releases said journal and frees the roll, means for controlling the position of the said bearing-member and thereby determining its 105 engagement with the journal and its release thereof, and means acting to swing automatically the arm and bearing-member away from the journal upon the release of 110 the latter.

6. The combination of a movably mounted journal-bearing member, an operating lever operatively connected therewith and where-by such member may be turned into a position to receive or discharge a roll-journal, and from such position into one which retains the roll-journal, and a gravitating support for the said journal-bearing member which automatically carries the latter away 115 120 from the roll-journal when the said journal is released.

7. The combination of a movably mounted journal-bearing member, an operating lever operatively combined therewith through 125 connections by which such member may be turned from a position providing for the reception and discharge of a roll-journal into one which retains the roll-journal, and by which also the journal-bearing member is 130

locked automatically in the latter position, and a gravitating support for the said journal-bearing member which automatically carries the latter away from the roll-journal 5 when the said journal is released.

8. The combination with a frictional driving roll or cylinder, a support which gravitates toward the said roll or cylinder, and a roll driven by surface contact with the 10 latter, of a journal-bearing member carried by said gravitating support, and an operating lever operatively connected with said member and whereby the latter may be given a position to receive or discharge a 15 journal of the said roll, and may be shifted from such position into one which retains the roll-journal, the gravitating movement of said support acting automatically to carry the bearing-member away from the roll-journal 20 upon the release of the latter.

9. The combination with a frictional driving roll or cylinder, a support which gravitates toward the said roll or cylinder, and a roll driven by surface contact with the 25 latter, of a journal-bearing member carried by said gravitating support, and an operating lever pivoted upon said gravitating support operatively connected with said member and whereby the latter may be given a 30 position to receive or discharge a journal of the said roll, and may be shifted from such position into one which retains the roll-journal, the gravitating movement of said support acting automatically to carry the bearing-member away from the roll-journal 35 upon the release of the latter.

10. In a roll-support, in combination, a

journal-bearing member mounted upon a pivot, an operating lever having a crank, a link or links connecting said crank with one 40 or more crank-pins upon the said journal-bearing member, and stops to arrest the relative movement of the parts with the aforesaid crank and link or links in position to form a toggle-lock to retain the said journal-bearing member in position to hold the journal of a roll. 45

11. In combination, a roll-supporting device comprising a journal-bearing mounted upon a pivot, operable into position to receive the journal of a roll advanced thereto in a horizontal direction, and from such position into position to retain the roll during rotation thereof. 50

12. In a roll-support, in combination, a 55 swinging supporting arm, a roll-supporting member pivotally connected with said arm and adapted to engage, support, and release the journal of a roll, an operating lever pivotally connected with said arm and provided with a crank, a link or links connecting said crank with one or more crank-pins upon the aforesaid roll-supporting member, and stops to arrest the relative movement of the parts when the aforesaid crank and link or links 60 are in position to form a toggle-lock to prevent said roll-supporting member from releasing the roll-journal. 65

In testimony whereof I affix my signature in presence of two witnesses.

LORENZ FLICK.
